DOOR LATCH HANDLE

Claude Teggelaar, Grand Rapids, Mich., assignor to
Wolverine Industries, Inc., Grand Rapids, Mich.

Filed Jan. 11, 1973, Ser. No. 322,626

Term of patent 14 years

Int. Cl. D8—06

U.S. Cl. D8—170

FIG. 1

FIG. 2

FIG. 3

FIG. 4

FIG. 5

FIG. 1 is a perspective view on a reduced scale, showing a door latch handle from the front and one side which embodies the new design;

FIG. 2 is a front elevational view of the door latch handle shown in the previous figure;

FIG. 3 is a side elevational view of the door latch handle shown in the previous figures, as seen from the left side;

FIG. 4 is an overhead plan view of the door latch handle shown in the previous figures; and

FIG. 5 is a sectional bottom plan view of the door latch handle shown in the previous figures, taken through the plane 5—5 of FIG. 3.

I claim:

The ornamental design for a door latch handle, substantially as shown.
